UNITED STATES PATENT OFFICE.

THEODORE N. MATHIAS, OF MILWAUKEE, WISCONSIN.

DESIGN FOR A REIN-SUPPORT.

SPECIFICATION forming part of Design No. 35,761, dated February 18, 1902.

Application filed December 23, 1901. Serial No. 87,037. Term of patent 14 years.

To all whom it may concern:

Be it known that I, THEODORE N. MATHIAS, residing at Milwaukee, in the county of Milwaukee and State of Wisconsin, have invented and produced a new and original Design for Rein-Supporters, of which the following is a description, reference being had to the accompanying drawings, which are a part of this specification.

10 My invention has relation to a new and original design for a rein-supporter.

In the accompanying illustrations, Figure 1 is an edge view of a rein-supporter, showing my new design; and Fig. 2 is a top view thereof.

15 As shown in the drawings, the leading or material feature of my design consists of a

base having a solid central portion A, and open or looped portions B B, a stem C, projecting from the outer face of the central solid portion, and a short stud or tongue D, projecting from the inner face of the solid central portion.

Having described my invention, what I claim as new, and desire to secure by Letters Patent, is—

The design for a rein-supporter, as herein shown and described.

In testimony whereof I affix my signature in presence of two witnesses.

THEODORE N. MATHIAS.

Witnesses:

A. L. MORSELL,
ANNA V. FAUST.
